Des. 100,597

EMBROIDERED OILCLOTH

Filed July 6, 1936

Martin H. Ehrman
INVENTOR

UNITED STATES PATENT OFFICE

100,597

DESIGN FOR EMBROIDERED OILCLOTH

Mortimer H. Ehrman, New York, N. Y.

Application July 6, 1936, Serial No. 63,647

Term of patent 3½ years

To all whom it may concern:

Be it known that I, Mortimer H. Ehrman, a citizen of the United States of America, residing in Manhattan, county of New York and State of New York, have invented a new, original, and ornamental Design for Embroidered Oilcloth, of which the following is a specification, reference being had to the accompanying drawing, forming part thereof, wherein,

The figure is a plan view of a piece of embroidered oilcloth showing my new design.

I claim:

The ornamental design for embroidered oilcloth, substantially as shown.

MORTIMER H. EHRMAN.
